UNITED STATES PATENT OFFICE.

FRÉDÉRIC DE DIETRICH, OF PARIS, FRANCE, ASSIGNOR TO DE DIETRICH & CIE., OF NIEDERBRONN-LES-BAINS, BAS-RHIN, FRANCE, A CORPORATION OF FRANCE.

STIRRING APPARATUS.

Application filed July 6, 1921. Serial No. 482,690.

To all whom it may concern:

Be it known that I, FRÉDÉRIC DE DIETRICH, citizen of the Republic of France, residing at 16 Rue Gustave Zede, Paris, Seine, France, have invented certain new and useful Improvements in or Relating to Stirring Apparatus, of which the following is a specification, reference being had therein to the accompanying drawing.

- 10 For the purpose of obtaining reactions between different substances, the chemical industry needs apparatus by means of which the substances to undergo treatment can be intimately mixed.
- 15 The problems that present themselves are as varied as the substances to be treated. For each particular case, it has been necessary to construct stirrers that will suit the conditions presented.
- 20 To effect the mixture of, or to commingle intimately two liquids of different specific weights so that the one can react on the other, is in particular, one of the most difficult problems to settle.

25 Apparatus employed up to the present for solving this problem has the drawback of causing a great expenditure of motive force. In fact, the beaters or stirrers of the apparatus meet with a great resistance 30 since they have to turn at very great speed to prevent the heavier liquid sinking to the bottom of the containing vessel.

The problem is still more complicated when the heavier liquid is used in a relatively small quantity. The beaters or stirrers being necessarily a short distance from the bottom of the vessel do not succeed in raising and carrying along the heavy liquid.

The invention relates to a stirrer essentially characterized by the fact that it enables, with a minimum expenditure of motive force, the intimate mixture of two liquids of different specific gravities to be effected, the heavier liquid being easily captivated at the bottom of the vessel and projected into the mass of the lighter liquid, whatever may be the relative proportion of the two liquids.

In the accompanying drawing, given by way of example:—

Fig. 1 is a vertical section of a stirring

apparatus arranged according to the invention.

Fig. 2 shows a modification of the stirrer itself.

The apparatus comprises a stationary vessel 1 having a coned bottom 2 and a hollow stirrer substantially of ogival form (Fig. 1) or of cylindro-ogival (Fig. 2) or even conical shape, whose pointed end 4, 60 pierced with an orifice 5, is disposed in the immediate vicinity of the lower part of the portion 2 in which the heavier liquid is accumulated to a level so much the higher as the conicity of the bottom portion 2 of the vessel is more pronounced. Orifices 6 are provided in the wall of the stirrer and a circular rib or projection 7 is formed on the outside of the stirrer just below the orifices 6.

70 The stirrer or agitator is supported and operated by means of a spindle 8, which is mounted in any appropriate manner and on which is fixed a frictional or toothed bevel wheel 9 that is in contact or mesh with a similar member 10 adapted to be operated by the driving shaft 11.

75 On turning rapidly about its vertical axis, the stirrer 3 drags along by reason of friction, the liquid contained in the vessel 1, and also the liquid contained in the interior of the stirrer. The surface of the liquid in the vessel and in the stirrer assumes the forms shown in Fig. 1.

80 The heavy liquid L is thus caused, by centrifugal force to rise along the internal wall of the stirrer as indicated by the arrows and to reach the level of the orifices 6 through which it is projected to the outside in very small drops which, after traversing the space of air between the outer wall of the stirrer and the surface of the light liquid in the vessel, penetrate into this liquid with a velocity equal to the tangential velocity of the stirrer and then return 85 to the bottom of the vessel following a spiral course through the light liquid. This has the effect of prolonging the time during which the heavy liquid, in very divided condition is in intimate contact with the light 90 liquid.

95 This dividing up of the heavy liquid and

the prolonged time of contact between the two liquids are very favourable for promoting chemical reactions. The flow of a portion of the heavy liquid, owing to adhesion, along the external wall of the stirrer is rendered impossible by the projection or rib 7.

The power required for this stirrer is insignificant compared with what is required in known systems, since, in spite of the great speed of rotation, friction between the stirrer and the liquid is diminished considerably for the two following reasons:

1.—The liquid turns with a speed which is nearly equal to that of the stirrer, consequently the relative speed between the two elements is very small.

2.—The quicker the system turns and the more the exterior of the stirrer is freed of or out of contact with the liquid whose surface takes the form of a paraboloid of revolution whose vertex is so much the nearer to the point of the stirrer, as the speed of the latter increases.

Under these conditions, friction between the stirrer and the liquid is partially replaced by friction between the stirrer and air, the air effecting much less resistance.

The apparatus can be constructed of any appropriate materials, and in particular of enamelled iron.

What I claim is:

1. The method of stirring two liquids of different specific gravities, which consists in confining the liquids in a suitable container, producing a vortex in the upper part of the liquid and simultaneously withdrawing heavier liquid from the bottom of the container and projecting it horizontally from points within the hollow of the vortex at acute angles to the sides thereof, whereby the heavier liquid is caused to travel downward through the lighter liquid in spiral paths.

2. The method of stirring two liquids of different specific gravities, which consists in confining the liquids in a suitable container and subjecting them to the action of a rapidly rotating hollow member having an orifice in its lower end and suitable lateral discharge orifices, whereby a vortical motion of the upper lighter part of the liquid is produced and the heavier liquid at the bottom of the container flows up along the inner walls of the hollow member and is projected laterally into the inner sides of the vortex at acute angles to the surfaces thereof and thus caused to travel downwardly through the lighter liquid in spiral paths.

3. The method of stirring two liquids of different specific gravities, which consists in confining the liquids in a suitable container, producing a vortex in the upper part of the liquid and simultaneously withdrawing the heavy liquid from the bottom of the

container and projecting it in a number of fine streams laterally from points within the vortex and at acute angles to the sides thereof.

4. A stirring apparatus of the kind described comprising a receptacle adapted to contain liquids of different specific gravities, and a hollow member rotatably mounted in said receptacle on a vertical axis and extending to a point close to the bottom of said receptacle, said hollow member having a narrow orifice at its lower end and a plurality of small lateral discharge openings adjacent its upper end and having a smooth unobstructed interior, whereby when said hollow member is set in rapid rotation the heavier liquid from the bottom of the receptacle flows up along the inner walls of said member and is projected through said discharge openings in a number of fine streams into the body of the lighter liquid.

5. A stirring apparatus of the kind described comprising a receptacle adapted to contain liquids of different specific gravities, and a hollow member rotatably mounted in said receptacle on a substantially vertical axis and having a tapering end open at the bottom extending close to the bottom of said receptacle and having a series of small lateral discharge openings adjacent its upper end, the interior of said hollow member being entirely unobstructed.

6. A stirring apparatus of the kind described, comprising a receptacle having a conical bottom and having a circular cross section throughout with smooth unobstructed interior walls, a hollow member of substantially ogival shape disposed in said receptacle substantially coaxial therewith, the lower end of said member being open and disposed close to the bottom of said receptacle and said member having a plurality of lateral discharge openings adjacent its upper end, a shaft attached to the upper end of said member and means for rotating said shaft.

7. A stirring apparatus for mixing liquids of different specific gravities, comprising a receptacle for the liquids having a circular cross section throughout with smooth unobstructed interior walls, a hollow member having a closed upper end and a tapering lower end, the lower or smaller end of said member being open and disposed close to the bottom of said receptacle, said member being of circular cross section and having smooth unobstructed interior walls and said member having a plurality of small lateral discharge openings adjacent its upper end, a shaft attached to the upper end of said member and means for rotating said shaft.

8. A stirring apparatus for mixing liquids of different specific gravities, comprising a receptacle for the liquids having a cir-

cular cross section with smooth unobstructed interior walls, a hollow member having a tapering lower end with a small orifice there-in disposed close to the bottom of said re-
ceptacle, said hollow member being of cir-
5 cular cross section with smooth unobstructed interior walls and having a number of small discharge openings adjacent its upper end

and having an annular rib located below said openings, and means for rotating said 10 member.

In testimony whereof I affix my signature.

FRÉDÉRIC DE DIETRICH.
